UNITED STATES PATENT OFFICE.

JOHN KRESS, OF NEW ROCHELLE, NEW YORK.

ABRADING-MACHINE.

1,132,192.

Specification of Letters Patent. Patented Mar. 16, 1915.

Application filed June 20, 1914. Serial No. 846,265.

To all whom it may concern:

Be it known that I, JOHN KRESS, a citizen of the United States, residing at New Rochelle, in the county of Westchester and State of New York, have invented certain new and useful Improvements in Abrading Devices, of which the following is a specification.

My invention relates to an abrading device particularly designed for sharpening knives and an object of the invention is to provide a device of this character particularly adapted for household purposes which can be supplied with different grinding, buffing and polishing tools, which can be readily and quickly inserted therein to perform their different functions.

Other objects of the invention are to provide such a device with the least possible number of separate parts, to arrange the parts so that they may be readily dismounted for cleaning and to inclose the gearing so to protect the operator and at the same time to provide a device which can be cheaply marketed.

Various other objects and advantages of the invention will be in part obvious from an inspection of the accompanying drawings and in part will be more fully set forth in the following particular description of one form of mechanism embodying the invention, and the invention further consists in certain new and novel features of construction and combination of parts hereinafter set forth and claimed.

In the accompanying drawings: Figure 1 is a front elevation partly in vertical section showing a preferred embodiment of my invention; Fig. 2 is a side elevation of the right hand side of the device shown in Fig. 1; and Fig. 3 is a rear side view of one of the abrading tools.

There is shown a support comprising a base plate 1 which may be fastened to a suitable supporter, such as the kitchen table 2, by means of a suitable clamp 3 as is usual with devices of this character. Fixed to the base plate is a pair of upright inclosing casings 4 and 5, journaled within the lower portion of which is a driving mechanism comprising a shaft 6 rotated by any suitable means as by the crank handle 7. Fixed to the shaft and protected by the casings 4 and 5 are a pair of gear wheels 8 and 9. The gear wheel 8 is in mesh with a gear wheel 10 which is removably mounted on the non-

circular portion 11 of a stub shaft 12 forming a part of a removable tool 13 which is journaled in the casing 4 above the shaft 6. This tool has a face plate 14 fixed to the inner end of the shaft 12 and has suitable abrading material 15 affixed to the face opposite the shaft. This abrading material may be emery, soapstone, carborundum, felt, cloth, or any other substance used for grinding, polishing or buffing knives. In order to give the working faces of these abrading tools a slight inclination for a purpose hereinafter described the shaft 12 is inclined and the gear wheels 8 and 10 may be slightly beveled but with the use of large commercial gear wheels this is usually unnecessary. The tools are removably held in place by means of a spring pin 16 engaging in a peripheral groove 17 in the shaft 12. A bearing 18 is hinged to the upper edge of the casing 5 and forms a continuation of the same paralleling the upper portion of the casing 4.

Removably journaled in the plate 18 is a tool 19 resembling the tool 13 and when in operative position as shown in full lines in Fig. 1 coacting therewith to form an angled opening 20 equal to or preferably slightly greater than the angle of the cutting edges of the knife to be sharpened. The tool 19 is driven from the driving gear wheel 9 through the gear wheel 21 which resembles the gear wheel 10.

A U-shaped yoke 22 has its ends pivoted to the plate 18 above its hinged connection with the casing 5, incloses the casing 4 and has a thumb screw 23 threaded therethrough and bearing on said casing to maintain the tools adjustable relative to each other when in their operative position.

In operation the screws 23 are loosened to permit the plate to be moved into an inoperative position such as is shown in the dot and dash lines of Fig. 1 and by withdrawing the pins 16 any desired character of tool may be mounted in the casing 4 and plate 19 and then fastened in place. Instead of the gear wheels 10 and 21 being loose, they may form a fixed part of each tool, but the loose wheels form a more economical structure. When set with the desirable tools the plate 18 is drawn toward the full line position shown in Fig. 1 and held from outward movement by means of the engagement of the screw with the outside of the casing 4. The knife is then wedged into the angled opening 20 between the working faces of the

tools and the handle 7 rotated until the desired surface is produced on the knife when another tool may be substituted as described.

- By means of a structure such as described 5 a simple household article is produced which may be conveniently set up and in which different kinds of abrading surfaces may be conveniently mounted without the use of screwdrivers or other fastening tools. 10 By simply turning the thumb screw any working angle may be obtained between the abrading surfaces thereby to accommodate different types of knife blades and the entire device is inclosed and the parts are arranged 15 to mutually brace each other with the use of the least possible amount of material.

Although I have shown only one form of mechanism embodying my invention, it is obvious that various changes within the skill 20 of the mechanic may be made therein without departing from the spirit of the invention, provided the means set forth in the following claims are employed.

Having thus described my invention, I 25 claim:

1. In a device of the class described, a support having an abrading tool removably journaled therein, a hinged plate movable relative to said support, a second abrading 30 tool journaled in said plate and movable therewith into an angular portion relative to said first named abrading tool, a yoke pivoted to said hinged plate and inclosing said support, a thumb screw carried by said yoke 35 and bearing on said support to maintain said tools in their operative position and means for driving said tools.
2. In a device of the class described a gear inclosing casing having a journal in 40 the form of a hub projecting therefrom, a replaceable abrading member having a shaft fixed thereto and removably mounted in said journal and means passing through said hub for locking said shaft in position, 45 said shaft having a non-circular portion within the casing, a gear wheel removably

mounted on said portion to rotate the shaft and a driving gear wheel mounted in said casing, positioned below and adapted to mesh with said removable gear wheel. 50

3. In a device of the class described, a support, a driving shaft journaled in said support, a pair of gear wheels fixed to said shaft, a pair of coacting abrading members removably mounted for rotary movement 55 and normally in mesh respectively with said gear wheels one of said members movable relative to the other member to permit the substitution of other abrading members and means for maintaining said members in operative position relative to each other. 60

4. In a device of the class described, a support, a driving mechanism mounted in said support, a journal plate hinged to said support, an abrading member removably mounted on said journal plate, means engaging said plate for maintaining said member in an operative position and a driving connection between said mechanism and said abrading member when held in operative position. 70

5. In a device of the class described, a pair of oppositely disposed abrading members rotatably mounted with their adjacent faces disposed at a slight angle to each other to permit the insertion of a blade therebetween to be sharpened simultaneously on opposite sides and manually actuated means for simultaneously rotating said members. 75

6. In a device of the class described, a pair of rotary abrading tools having oppositely disposed working surfaces adapted to be positioned at a slight angle to each other and means for varying the axis of rotation of one of said tools relative to the axis of rotation of the other tool. 80

Signed at New Rochelle in the county of Westchester and State of New York this 15th day of June A. D., 1914.

JOHN KRESS.
